UNITED STATES PATENT OFFICE

IGNAZ SCHAUER, OF VIENNA, AUSTRIA

FOLDING TABLE

Application filed October 11, 1929, Serial No. 399,015, and in Austria March 11, 1929.

Folding tables are known, the table top of which when not in use forms a box for taking the table legs and possibly also articles such as folding chairs.

Such tables are open to the objection that they sag in the middle, when the table is lifted by its top.

It has been endeavoured to overcome this objection by inserting clamps from below 10 onto the adjoining edges in the middle.

The present invention is based on the idea that the above mentioned drawback can not be redressed by means of special clamps or similar devices, but only by suitably fashioning 15 the leg ends swivelably fastened on the front parts of the box.

For this purpose the legs arranged on each half of the box and swivelable in common, are connected by means of a rod. These legs 20 are eccentrically linked to the inner side of the front parts of the box by bearing shields, which, when the legs are in position for use, rest against the under side of the table top and at the same time against the inside of the 25 front of the box.

In the accompanying drawings an embodiment of the invention is illustrated by way of example.

Fig. 1 is a view from below of the unfolded 30 table.

Fig. 2 shows in top plan view of the folded table, the table plate removed.

Legs 1 are attached to plates 3 pivotally mounted on the inside of the box frame 2 and 35 enlarged towards their base, their pivot being placed outside of the longitudinal axis of the legs 1 towards the middle of the box.

Thus the plates 3 form a support for the table top and rest not only against the top 40 but also against the front part of the box.

Each pair of legs is coupled by means of a connecting rod 4, thus permitting the simultaneous swivelling of each pair of legs, said 45 legs when turned down securely holding foldable chairs or other articles within the box.

The pairs of legs 1 are connected to each other by bows 5, which are composed of several parts. The connection between the legs

1 and the bows 5 is effected by shiftable sleeves 6.

I claim:

1. A folding table, comprising in combination with pivotable legs, a table top composed of two hingedly connected parts in box shape adapted to accommodate the folded legs and other articles such as folding chairs, and bows with sleeve-like terminals for connecting the one with the other the legs on the long sides of the table, said bow being directed transversely to the hinge axis of the two box-shaped top parts in the extended position of the table.

2. A folding table as specified in claim 1, comprising in combination with the box-shaped hingedly connected top halves and the pivotally mounted legs, plates pivotally mounted one in each outer corner in the box-shaped top halves each plate serving as pivot for one leg each plate enlarged so that the pivot axis of the legs extend parallel to the hinge axis of the box-shaped table top, and boards rigidly connecting the legs on the ends of said table top.

In testimony whereof I affix my signature.

IGNAZ SCHAUER.
